By Southgate & Southgate, Attn:

UNITED STATES PATENT OFFICE.

CHARLES W. WITTINGTON, OF LAVERHILL, MASSACHUSETTS, ASSIGNOR TO
WITTINGTON & ROYAL, OF SAME PLACE.

DESIGN FOR A DUST-GUARD FOR CORNERS.

SPECIFICATION forming part of Design No. 30,685, dated May 2, 1899.

Application filed March 18, 1899. Serial No. 709,692. Term of patent 7 years.

To all whom it may concern:

Be it known that I, CHARLES W. WITTINGTON, a citizen of the United States, residing at Laverhill, in the county of Essex and State of Massachusetts, have invented a new and useful Design for Dust-Guards for Corners, of which the following is a specification.

The object of this invention is to provide a new and original design for a three-sided dust-guard for corners.

The accompanying drawings give and convey to those skilled in the art a clear understanding of the design and is sufficient to enable such persons to apply the design to a three-sided dust-guard.

In said drawings, Figure 1 is a front view of a dust-guard for corners embodying the design; and Fig. 2 is a sectional view thereof, taken on the line 2 2 of Fig. 1.

The design as herein illustrated comprises an ornament or figure for occupying the central part of the surface of a three-sided dust-guard for corners and ornamental work or figures for each corner of a three-sided dust-guard for corners.

What I claim, and desire to secure by Letters Patent of the United States, is—

The design for a dust-guard for corners, substantially as shown.

In testimony whereof I have hereunto set my hand in the presence of two subscribing witnesses.

CHARLES W. WITTINGTON.

Witnesses:

CHARLES W. ROYAL,
JOSEPH H. PEARL.
